UNITED STATES PATENT OFFICE.

CARL ROGER DARNALL, OF WASHINGTON, DISTRICT OF COLUMBIA.

APPARATUS FOR PURIFYING LIQUID.

1,178,499.

Specification of Letters Patent. Patented Apr. 11, 1916.

Application filed September 23, 1911. Serial No. 650,929.

To all whom it may concern:

Be it known that I, CARL R. DARNALL, a citizen of the United States of America, residing at Washington, in the District of Columbia, have invented certain new and useful Improvements in Apparatus for Purifying Liquids, of which the following is a specification.

My invention relates to apparatus for purifying liquids and has special reference to means for purifying water and sewage by the use of dry chlorin gas.

The object of the present invention is to reduce the number of parts necessary for the successful operation of the apparatus, thereby effecting an economy in installation and maintenance and to obtain a more direct operation than has been heretofore possible.

20. The invention is illustrated in the accompanying drawings and will be hereinafter fully described with reference thereto, the novel features being subsequently more particularly pointed out in the appended claim.

25. In the drawings, Figure 1 is a view partly in elevation and partly in section of my improved apparatus, the figure being more or less diagrammatic in character. Fig. 2 is a plan view. Fig. 3 is a detail sectional elevation of a portion of the apparatus, showing a modification. Fig. 4 is a detail elevation, showing a further modification. Fig. 5 is an enlarged detail section.

30. The liquid to be treated is conducted from any source of supply, indicated in the drawings by a tank 1, through a main or conduit 2 which is provided with cut-off valves 3 and 4 and in which is interposed a mixing chamber 5 of any preferred suitable construction, while beyond the said mixing chamber a goose-neck 6 is provided in the conduit to form a water seal which will prevent loss of the gas, as will be readily understood. The valve 3 is normally open 35 so as to permit a constant flow of liquid therethrough, while the valve 4 is opened or closed accordingly as it is desired to permit or arrest the operation of the apparatus, the valve 4 being of greater capacity than the valve 3, so that when the said valve 4 is opened the liquid will flow freely through the conduit and when the valve 4 is closed the water will be held in the conduit and will rise in the pipe by which the purifying agent is admitted to the conduit and thereby

create a back pressure upon the said agent which will arrest the flow of the same. Should it be necessary to repair or clean any part of the apparatus, the valve 3 is closed and the liquid is consequently prevented from entering the conduit, so that the conduit may be drained, as will be readily understood. The dry chlorin gas is supplied from a drum, cylinder or other receptacle 7 from which a pipe 8 leads to a gas conductor 9, a cut-off valve 10 being provided in the pipe 8 by which the flow of gas may be permitted after the cylinder or drum 7 has been coupled to the said pipe and a similar pipe 11, equipped with a valve 12, is coupled to the gas pipe 9 so that a plurality of drums may be provided and successively cut into use as the charge drawn upon is exhausted. A pressure gage 13 is fitted on the gas conveying pipe 9 whereby the pressure of the gas in the drum which is in use will be accurately noted and the attending operator will be apprised of the condition of his supply, so that he may cut-out an exhausted drum and cut-in a fresh drum in ample season to prevent any accidental or premature cessation of the operation of the apparatus. Beyond the pressure gage 13, the gas pipe 9 is equipped with a controlling valve 14 and, in the arrangement shown in Fig. 1, the stem of this valve is provided with a crank disk 15, to which a lever 16 is secured, said lever being equipped with an adjustable weight 17, so that the working pressure of the gas may be varied to any desired degree. A pressure gage 18 is mounted on the gas pipe 9 beyond the controlling valve 14, so as to indicate the working pressure of the gas, and beyond the said gage 18 the pipe is provided with a short branch 19 leading into a gas receiver 20. Within this gas receiver 20 is a flexible diaphragm 21, at the center of which is provided a socket 22 projecting through the casing of the receiver and having a seat 23 secured therein by a locknut 24, as shown most clearly in Fig. 5. The seat 23 comprises a stem 25, threaded into the socket 22 and having the lock-nut 24 thereon, and a head 26 at the outer end of said stem provided with a concave recess or socket 27, in which is fitted and held by gravity a ball 28 on the end of a stem 29, formed preferably on the shorter arm of a lever 30, the longer arm of which is con-

nected by a link 31 with the shorter arm of a lever 32, the longer arm of said lever 32 being connected by a link 33 with the weighted lever 16, as shown. This system 5 of levers constitutes an amplifying mechanism by which the motion of the diaphragm will be transmitted directly to the controlling valve so that the said valve will be opened or closed under any variation in 10 the pressure in the gas receiver. It will thus be seen that the apparatus will respond very quickly to variations in the working pressure and that a very slight change in the tension of the diaphragm due to variation 15 in the pressure of the gas will cause a positive movement of the controlling valve so as to open or close the same and thereby maintain a constant low working pressure of the gas. The quantity of gas permitted to flow to 20 the conduit will also be thus automatically regulated and adjusted to the quantity of water being treated, so that there will be no waste of the gas during the operation of the apparatus. The gas conveying pipe, beyond 25 the branch 19, is preferably formed into a U-shaped member 34 from the discharge leg of which a branch 35 leads into a pipe or tube 36, which opens directly into the mixing chamber 5. This pipe or tube 30 36 may be provided with slots 37 covered with transparent material, so that the attendant may readily perceive whether or not gas is passing to the mixing chamber, and as the height to which the water will 35 rise in the said tube 36 will indicate the pressure of the gas in the said tube, the gage 18 is not indispensable.

The U-shaped member 34 is filled with charcoal, fine clay or similar material, indicated at 38, so as to retard the flow of gas therethrough and permit it to enter the mixing chamber only in the minute quantities necessary for the proper treatment of the liquid. This retarding material 40 also serves to retain the dry condition of the gas, so that its action upon the water will not be impaired and corrosion of the parts through which it passes will be prevented. The gas conducting pipe is also 45 preferably equipped with valves 39 and 40, by which the flow of gas may be cut off entirely when it is desired to repair, renew or clean any of the parts.

The operation of the apparatus is thought 50 to be evident from the foregoing description. The several parts of the apparatus being fitted together in the described relation, the gas containing drum is cut into operation by opening the valve immediately adjacent 55 thereto, so as to permit the gas to flow into the gas conveying pipe 9. As initially there is no pressure other than atmospheric pressure in the receiver 20, the controlling valve 14 will be open and the gas will at once 60 flow into said receiver and act upon the

diaphragm 21, so as to actuate the amplifying levers and close the controlling valve, and when the pressure of the gas is equal to or slightly exceeds the weight 17, the valve will be fully closed. The valves 39 and 40 70 being opened, gas will be permitted to flow into the mixing chamber 5, and the valves 3 and 4 being open, the water will flow through the conduit and will absorb the gas in the mixing chamber and be thereby purified. Should it be desired to arrest the operation, it is only necessary to close the valve 4 when the water will rise in the tube or pipe 36 and thereby create a back pressure 75 upon the gas sufficient to raise the diaphragm 21 and completely cut off the inflow of the gas. While the water is flowing through the conduit, the gas will be supplied thereto under a uniform low pressure 80 inasmuch as the diaphragm 21 will drop 85 as the gas is consumed and consequently, the controlling valve will be opened to permit the flow of a sufficient quantity of gas to keep the supply in the gas receiver constant. 90

Instead of the system of levers shown in Fig. 1, I may employ the arrangement shown in Fig. 3 in which the controlling valve 41 is provided with a depending stem 42, fitting into the seat on the diaphragm 95 and a spring 43 is coiled around said stem, so as to hold the stem firmly in its engagement with the seat. By varying the tension of the spring, the pressure necessary to operate the diaphragm may be adjusted to 100 the same extent that shifting of the weight 17 will accomplish that result in the arrangement shown in Fig. 1. As the diaphragm rises and falls, the stem 42 will necessarily follow the movement and thereby close or 105 open the valve 41, as will be readily understood. By reason of the ball and socket engagement of the stem and the seat on the diaphragm, the probability of binding of 110 the parts and the consequent clogging of their movement is obviated.

In very large plants, where it is not necessary to admit the gas in minute quantities to the water, I may employ the arrangement shown in Fig. 4. In this form of the device, the conduit 2 with its mixing chamber 5 and goose neck 6 are of the same form as those shown in Fig. 1, but the gas-conveying pipe leads directly from the gas receiver to the mixing chamber and the retarding tube 34 is dispensed with. The gas-conveying pipe, indicated at 44, is provided with a short horizontal portion 45 adjacent the cut-off valve 46 in the conduit and in the said horizontal portion 45 is a cut-off 115 valve 47. The cutoff valve 46 corresponds in its functions to the cut-off valve 4 shown in Fig. 1, but the stem 48 of said valve is extended above the operating hand wheel 49 and has a loose connection with the longer 120 125 130

arm of a lever 50. The shorter arm of this lever 50 has a loose connection with the depending stem 51 of the valve 47 and around the said stem between the end of 5 the lever 50 and a pin 52, inserted through the stem, is coiled a spring 53, as shown. In this arrangement when the valve 46 is closed, the longer arm of the lever 50 is drawn downward so that the shorter arm 10 thereof is caused to rise and the valve 47 under the combined influence of the lever and the spring 53 will be closed. When the valve 46 is opened, of course, by the upward movement of the stem 48, the valve 15 47 will be simultaneously opened. It will be observed that the lever 50 does not act directly upon the stem 51 of the valve 47, but acts against the spring 53, so that should additional movement of the stem 48 be necessary after the valve 47 is closed, the 20 lever will be cushioned against the spring 53 and the bending of the said stem 51 will be thereby prevented.

It will be understood, of course, that in 25 this form of the invention a cock, similar to that shown at 40 in Fig. 1, may be pro-

vided in the gas pipe to regulate the quantity of gas admitted to said pipe.

Having thus described my invention, what I claim is:

An apparatus for the purpose set forth comprising a gas conveyer, a gas receiver communicating laterally with the gas conveyer but otherwise closed and having a portion movable under pressure of the gas 30 in said conveyer, a controlling valve in said conveyer, a socket projecting from the movable portion of the gas receiver, a seat secured in said socket and having a concave recess in its outer extremity, and movable 35 devices having a rocking detachable engagement with the said concave recess, but normally retained in engagement therewith by gravity, said movable devices being connected with the controlling valve of the 40 gas conveyer.

In testimony whereof I affix my signature in the presence of two witnesses.

CARL ROGER DARNALL.
